[57] CLAIM

The ornamental design for a writing instrument pouch, as shown and described.

DESCRIPTION

FIG. 1 is a top plan view of a writing instrument pouch embodying the new design.

FIG. 2 is a bottom plan view thereof.

FIG. 3 is a front elevational view thereof.

FIG. 4 is a rear elevational view thereof.

FIG. 5 is a left side elevational view thereof.

FIG. 6 is a right side elevational view thereof; and,

FIG. 7 is a top plan view of a second embodiment, all other views being the same as shown in FIGS. 1-6 with the exception of the additional side cordings.

The broken line showing of a writing instrument in the pouch is for illustrative purposes only and forms no part of the claimed design.
